UNITED STATES PATENT OFFICE.

WALTER M. SCHWARTZ AND ELWOOD B. AYRES, OF PHILADELPHIA, PENNSYLVANIA,
ASSIGNORS TO THE PHILADELPHIA TEXTILE MACHINERY COMPANY, OF PHILA-
DELPHIA, PENNSYLVANIA, A CORPORATION OF PENNSYLVANIA.

FAN FOR DRYING-MACHINES.

1,351,696.

Specification of Letters Patent. Patented Aug. 31, 1920.

Application filed February 7, 1920. Serial No. 357,095.

To all whom it may concern:

Be it known that we, WALTER M. SCHWARTZ and ELWOOD B. AYRES, citizens of the United States, residing in Philadelphia, Pennsylvania, have invented certain Improvements in Fans for Drying-Machines, of which the following is a specification.

One object of our invention is to construct a drying apparatus in which the fan shafts are arranged vertically and the bearings for the shafts are located below the fans.

A further object of the invention is to construct a drying apparatus in which the fans are located on vertical shafts and the bearings and the gearing for each shaft are located in a longitudinal tunnel protected from the heat of the casing.

A still further object of the invention is to make the sides of the tunnel movable in order that access may be had to the gear casings and the bearings for the shafts.

In the accompanying drawings:

Figure 1 is a transverse sectional view through the drying apparatus illustrating our invention;

Fig. 2 is a plan view partly broken away;

Fig. 3 is an enlarged sectional view illustrating the upper and lower bearings for one of the fan shafts and the side walls of the tunnel turned back on their hinges, and

Figs. 4 and 5 are views of modifications.

1 is the casing of the drying apparatus. 2 are longitudinal drying chambers. In these chambers are the carriers 3 for the material to be dried. These carriers are shown in diagram and may be of any form desired and the number of chambers may vary. Located at the center of the casing is a heating and circulating chamber 4. In the upper portion of this chamber are heating pipes 5 arranged in any manner desired. 6 is a longitudinal tunnel in the present instance directly below the heating chamber 4. 15 is a longitudinal driving shaft located in the tunnel 6. 7 are vertical shafts arranged a given distance apart, and extending into the heating chamber 4. On the upper end of each vertical shaft in the heating chamber is a fan 8 and each shaft is supported by a lower bearing in a casing 9 and an upper bearing 10. These bearings are located in the tunnel and may be of any suitable construction.

In the present instance each of the cas-

ings 9 of the lower bearings is secured to 55 longitudinal angle beams 11 extending through the tunnel and the longitudinal driving shaft 15 is adapted to bearings in the casing 9, and is geared to each vertical shaft as shown in Fig. 3. Each of the bearings 9 and 10 contains lubricant, in the present instance, and this lubricant should be protected from the heat as much as possible, as it not only lubricates the bearings, but also the gearing in the lower casing, therefore both bearings of each vertical shaft are located in the tunnel, and as this tunnel is preferably open at each end there is a circulation of cool air therein. 65

The walls 12 of the tunnel are inclined, 70 in the present instance, and are hinged at the lower end 13 and bear upon a flanged plate 14 at the upper end which is preferably hinged at 16 to a fixed plate 17. When it is desired to enter the tunnel to reach one 75 or more of the bearings, one of the walls 12 can be pushed back, as shown in Fig. 3, so as to allow space for a workman to make the necessary repairs or adjustments. This also permits him to gain access to the fan 8, 80 which is above the plate 17. When the walls are down, as in Fig. 1, air circulates through the central heating chambers and the side drying chambers while the tunnel, in which the bearings for the fan shafts are 85 located, is open at each end so as to allow a current of air to pass through the tunnel and keep the bearings cool.

Furthermore, by locating the bearings in the tunnel they are not exposed to the dust 90 of a roof in which the drier is located.

In Fig. 4 we have illustrated a construction in which the walls 12^a of the tunnel are fixed. This construction may be used where the drier is of sufficient size to allow for a 95 large tunnel.

While we have shown a particular form of drying apparatus in which there are two drying chambers on each side of the tunnel, it will be understood that the invention can 100 be used with a type of drier having one or more drying chambers.

While we have shown the walls of the tunnel inclined, they may be vertical and the top plate may be extended, as in Fig. 5, but 105 we prefer to use the inclined walls as they allow for space for the circulation of heated air through the apparatus.

We claim:

1. The combination in a drier, of a drying chamber; a tunnel in the drier; a driving shaft extending into the tunnel; a vertical shaft driven from the driving shaft; bearings for the vertical shafts; and fans carried by the vertical shafts for circulating the air in the drying chamber.
2. The combination in a drier, of a centrally located tunnel in the lower portion thereof; a heating chamber above the tunnel; a drying chamber on each side of the tunnel; a longitudinal driving shaft extending into the tunnel; a series of vertical shafts geared to the longitudinal driving shaft; and a fan at the upper end of each vertical shaft, the bearings for each vertical shaft and the bearings for the longitudinal shaft being located in the tunnel.
3. The combination in a drier, of a longitudinal tunnel in the lower portion thereof; a heating chamber above the tunnel; a drying chamber at the side thereof; a longitudinal shaft extending into the tunnel; a series of vertical shafts geared to the longitudinal shaft and projecting through the roof of the tunnel; a fan on each vertical shaft within the heating chamber, the bear-

ings for the shafts being located in the tunnel, the side walls of the tunnel being movable so that they can be pushed back to allow sufficient space for a workman to pass into the tunnel.

4. The combination in a drier, of a centrally located tunnel; a heating chamber above the tunnel; and drying chambers through which the heated air circulates, said tunnel being open at both ends and having pivoted side walls which can be pushed back so that access can be readily had to the interior tunnel, circulating means in the drier and driving mechanism for the circulating means located in the tunnel.

5. The combination in a drier, of a heating chamber, a drying chamber, and a tunnel located in the lower portion of the drier; a driving shaft extending into the tunnel, a vertical fan shaft geared to the driving shaft, said fan shaft extending through the roof of the tunnel and a fan on the upper end of said shaft to circulate air through the heating and drying chambers, bearings for the vertical shaft located in the tunnel.

WALTER M. SCHWARTZ.
ELWOOD B. AYRES.
